UNITED STATES PATENT OFFICE.

ROBERT H. KAISER, OF CHICAGO, ILLINOIS.

HEADLIGHT.

1,303,328.

Specification of Letters Patent. Patented May 13, 1919.

Application filed November 27, 1917. Serial No. 204,208.

To all whom it may concern:

Be it known that I, ROBERT H. KAISER, a citizen of the United States, residing at Chicago, in the county of Cook, State of Illinois, have invented certain new and useful Improvements in Headlights; and I do hereby declare the following to be a full, clear, and exact description of the invention, such as will enable others skilled in the art 10 to which it appertains to make and use the same.

This invention relates to automobile headlights.

The object of the invention is to provide a 15 headlight for automobiles which, while diffusing a bright light over a large area, avoids any glare which will blind the drivers of approaching cars. The invention is based upon the principle of indirect lighting, but utilizes practically the same amount of reflecting or radiating surface as is at present customary in automobile headlights.

A further object of the invention is to provide such a structure which is not only capable 25 of inexpensive embodiment into a new headlight, but can also be manufactured as an attachment for headlights already in use.

With the above objects in view, and such 30 others relating to the details of construction, as may hereinafter appear, my invention will now be fully set forth and described, reference being had to the accompanying drawings.

35 In the drawings:—

Figure 1 is a front elevation of a lamp, Fig. 2 is a longitudinal section therethrough,

Fig. 3 is a rear elevation of a lamp sup-

40 port,

Fig. 4 is an enlarged transverse section therethrough,

Fig. 5 is a perspective view of an annular globe,

45 Fig. 6 is a detail fragmentary elevation showing the manner in which the lamp support and lamp casing are connected,

Fig. 7 is a section through a modified form of the invention, and

50 Fig. 8 is a fragmentary detail view thereof.

Referring more particularly to the drawings, 1 represents a shell casing formed in accordance with the accepted forms of automobile headlights, said casing having the side brackets 2 into which the standards of

a lamp support may be inserted. Also, the casing is provided with a conduit 3 by means of which a conductor core may be carried to the front of the lamp. Inserted within the 60 shell of the casing 1 is the reflector 4, which, in the present case is preferably formed of white translucent glass or other material. An annular flanged ring 5 secured to the interior of the casing 1 holds the reflector 4 in 65 position. The flanged ring 3 also provides a stop for an annular base 6 which carries a plurality of lamp sockets 7 within which the lamps 8 are inserted. The annulus or base 6 is preferably a hollow metal structure 70 into one of whose faces the sockets 7 are recessed, so that the lamps 8 project beyond the face of the annulus only to the extent of the bulb portions thereof. The several sockets 7, which are arranged in number ac- 75 cording to the power of the searchlight to be constructed, are wired together at the rear of the annulus, the connecting wires being then collected into a cord 9 which may be incased in the conduit 3. The annulus 6 is 80 hinged to the rim of the casing 1, preferably at the lower side of the latter so that the annulus may be swung downwardly and outwardly from the shell 1 for cleaning and repair purposes. A latch 10 at the upper side 85 of the shell 1 provides a means for locking the annulus in its closed position.

In order to properly diffuse the light from the lamps 8, the latter are covered with a circular globe 11 whose edges conform to 90° the inner and outer edges of the annulus 6, and is held thereon by means of clips 12 carried by the annulus. The globe 11 is also made of translucent material, such as "milk white glass."

95 The annulus or base 6 is covered, in its closed position, by means of a closure plate 13 of suitable design, the closure 13 having a lens inserted into an aperture 14 therein and being hinged to the shell 1 and being 100 mounted upon the shell in hinged relation after the manner of the usual lens frame of an automobile headlight.

In the form shown in Figs. 7 and 8, the device is constructed as an attachment for 105 headlights already in use. In its essential particulars relating to the base or annulus 6, the structure is the same as that described in the first form, but the shell is in the form of a comparatively wide collar which may 110 be slipped over the body or shell of an ordinary headlight, from the rear thereof, the

collar being contracted toward its rear end so as to conform to the shape of the headlights now most commonly in use, and around its rear margin is provided with a 5 series of spring fingers 16 which tend to firmly hold the collar in position. After the collar has been slid forwardly over the lamp body so that it projects beyond the forward edge and of a suitable distance the annulus 10 or base 6 with its lamps and globe, is inserted into the front end of the collar until it rests against the ring 5, after which the cover or closure 13 is placed in position. The lights, when lighted, throw their rays 15 against the reflector of the headlight, from whence they are transmitted in diffused relation on the roadway.

It will be apparent from the foregoing description that the headlight which I have 20 devised constitutes a very simple and inexpensive construction which will throw a highly diffused light upon a roadway with no glare or other dangerous or injurious characteristics. Furthermore, the device is 25 capable of instalment upon automobile lamps already in use, as well as in new lamps, the essential feature of the structure consisting in the proper arrangement of the annulus 6 with its plurality of lamps, within 30 the shell so that the light will be transmitted first to the rear in diffused relation, and then reflected forwardly onto the road.

What I claim as my invention is:—

1. An electric headlight comprising a casing having an annular mouth, an attaching ring in the mouth of the casing having its peripheral portion engaged within the periphery of said casing, the inner portion of the ring being inwardly offset, a bowl-shaped reflector having its mouth portion disposed about and secured on the inwardly offset portion of the rings, an annular lamp base seated in the outer portion of the ring and lamps carried by the inner side of said base.
2. An electric headlight comprising a reflector, an annular lamp base member secured at the mouth portion of the reflector and having its inner diameter substantially less than the diameter of said mouth portion

and a series of lamps on the inner face of 50 said base member whereby said base member shields the lamps from view at the front of the headlight.

3. An electric headlight comprising a bowl-shaped reflector, an annular lamp base 55 secured at the mouth portion of the reflector and having its inner diameter substantially less than the diameter of said mouth portion, a series of lamps on the inner face of said base member whereby said base 60 member shields the lamps from view at the front of the headlight, and a translucent shield for said lamps comprising an annular body of channeled cross-section and having its edge portions secured at the edge portions 65 of the inner face of the lamp base.

4. An electric headlight comprising a bowl-shaped shell, a bowl-shaped reflector of translucent light diffusing material disposed within the shell and spaced from the 70 walls thereof, a plurality of lamps disposed within the mouth portion of the shell, means for shielding the lamps from view at the front of the shell and translucent light diffusing covering for said lamps.

5. An electric headlight comprising a shell having an annular mouth portion, a bowl-shaped reflector in said mouth portion, an annular light base and shield member hingedly connected with the shell and 80 movable to lie within the mouth portion thereof, and a series of lamps mounted on the inner face of said member.

6. In a lamp of the class described, the combination of an outer shell, a reflector 85 contained therein, an annular channeled frame piece secured to the forward end of the shell, and an annular series of electric lamps positioned within said channeled frame piece, the latter serving to prevent 90 the rays from said lamps from passing directly through the front of the lamp casing.

In testimony whereof, I affix my signature in the presence of two witnesses.

ROBERT H. KAISER.
